UNITED STATES PATENT OFFICE.

HERBERT E. MARSHALL, OF NEW YORK, N. Y., ASSIGNOR TO HENRY W. AYLWARD,
OF BROOKLYN, NEW YORK.

BOTTLE-CAPPING MACHINE.

964,925.

Specification of Letters Patent. Patented July 19, 1910.

Application filed August 25, 1908. Serial No. 450,214.

To all whom it may concern:

Be it known that I, HERBERT E. MARSHALL, a citizen of the United States, residing at the borough of Brooklyn, city of New York, 5 in the county of Kings and State of New York, have invented a certain new and useful Improvement in Bottle-Capping Machines, of which the following is a specification, reference being had therein to the accompanying drawings, forming part thereof.

My invention relates to bottle-capping machines and particularly to machines which employ spinning rollers to spin on the caps. In machines of this class the spinning rollers are commonly made to spin continuously and very rapidly, and for the capping operation the cap and bottle-head are brought into contact with the rapidly spinning rollers. This, however, has not proved 20 a satisfactory method for applying such caps as the crown and similar caps on bottles having a comparatively small mouth, as for example, beer bottles.

One object of my invention is to overcome 25 the difficulties which have been encountered in this respect; and my invention is therefore particularly applicable to capping beer bottles and similar bottles, although, of course, it may be employed in any instance 30 to apply caps having a depending flange.

Other objects of my invention are reliability, simplicity and facility of operation.

Other objects and advantages of my invention will appear from the following description.

Instead of bringing the bottle-head into contact with the spinning head and continuously spinning rollers, I reverse the operation and bring the spinning head into contact with the bottle-head, thereby causing the spinning rollers to rotate and spin on the cap. To rotate the rollers as the spinning-head is brought into contact with the bottle-head, I employ the ordinary screw and nut 40 movement to convert rectilinear motion into circular motion. Instead of requiring prolonged spinning, as do caps which are applied by forming an inset ring to grip under a shoulder of the neck of the bottle, it is 45 essential to the successful application of the crown and similar caps which are to be removed in the well known manner, that the rollers rotate substantially but once around

the cap, and my invention includes means for accomplishing this result.

55

I shall now describe my invention with reference to the accompanying drawings, and shall thereafter point out my invention in claims.

Figure 1 is a side elevation partly in section of my improved bottle-capping machine. Fig. 2 is a central sectional detail elevation of the spinning head. Fig. 3 is a horizontal section of the spinning head on a plane indicated by the line $\alpha-\alpha$ of Fig. 2. Fig. 4 is a detail side elevation of the spinning head. Fig. 5 is an inverted plan view of the spinning head.

60

As shown in Fig. 1, the spinning head is secured to the reciprocating plunger, and moves with it. In the center of the spinning head is the vertical screw 1, which has a spline and groove connected with the head support 2, as shown, to prevent the screw from turning on a vertical axis, while allowing it to slide vertically in the support. The enlarged head 3 prevents the screw from passing entirely within the support, and thus separating the parts carried by the screw and those attached to the support. A nut 4 of brass or other suitable material contacts with the screw 1 and has a ring 5 at its upper end shown as screwed on, although it may be secured in any suitable way or made integral with the nut. Attached to the 70

frame 2 is a sleeve 6 having broad spiral grooves 7, the same pitch as the threads of the vertical screw, 1 the upper edges of which grooves are inclined as shown and serve as the part commonly called the cone, 80 in that they force inward the cap engaging spinning rollers. An annular space 8 is left between the sleeve 6 and the nut 4 for a purpose which will appear presently. The upper portion of the sleeve 6, however, for a distance equal to the width of the ring 5, is shouldered so as to contact with the ring. Between this portion of the sleeve and the ring 5 is provided a ball race 9. It is evident 85

now that as the support 2 is reciprocated, the sleeve 6 and the nut 4 are carried along with the support; and if the screw 1 is prevented from traveling along, as by contact with a bottle-head during the downward stroke, the threads of the nut 4, engaging with those 90 of the screw 1, cause the nut to be rotated. 95

100

105

The lower end of the screw 1 is reduced in diameter and a collar 10 encircles this reduced portion and is concentric with it. The upper side of this collar is provided with an 5 annular recess also concentric with the reduced portion of the screw. Seated in this recess beneath the shoulder on the screw and secured to the collar 10 is a cup-shaped sleeve 11, the vertical walls of which are 10 adapted to enter the annular space 8 as the head-support 2 and the parts carried by it are reciprocated. A collar 12 is pinned to the reduced end of the screw beneath the collar 10 and holds the collar 10 and the sleeve 15 11 in place against the shoulder of the screw.

The nut 4 is provided with keys 14, preferably two diametrically opposite, as shown in Fig. 2, and the sleeve 11 is provided with longitudinal grooves 13 within which the 20 keys 14 are adapted to slide. These parts are so proportioned in length that the keys 14 are in engagement in the grooves 13 in all positions of the parts, thus causing the sleeve 11 and the collar 10 to rotate with the 25 nut 4, in all relative positions thereof.

The collar 10 is provided on its periphery with four pairs of lugs or ears 15 between which are mounted the spinning mechanism. These consist of the usual spinning rollers 16 30 each suitably carried on an arm 17 having a hub 18 and an adjusting finger 19. Mounted on a common pivot with the hub 18 is the hub 21 and integral with the hub 21 and extending between the adjusting finger 19 and 35 the sleeve or cone 6, is the bearing block or finger 20, the inner face of which bears against the sleeve or cone 6 as shown. The spring 22 is fastened underneath the arm 17 and, bearing against the collar 10 between 40 the ears 15, tends to hold the roller 16 outward and press the finger 19 against the bearing block 20. An adjusting screw 23 in the end of the finger 19 enables the finger to be adjusted to and from the bearing block, 45 and consequently provides for adjustment of the rollers to and from each other, thus providing means for capping bottles having heads of varying diameters. The buffer head 24 is in the form of a nut 26, screwed 50 upon the lower end of the vertical screw 1 and having a bottle cap engaging recess 24 therein at its lower end. A lock nut 25 is shown to hold the buffer-head where it is adjusted. This quality of the buffer-head 55 enables it to be adjusted to fit bottle heads of various thickness.

To uniformly maintain the pressure on the top of the bottle during the capping operation, the head 3 of the screw 1 bears 60 against a spring 27 through a rock-lever 28 having a cam face 29. As the end of the rock-lever which bears against the head 3 is raised, the cam face 29 rolls down over a wheel 30 which is mounted in loose bearings and presses against the spring 27.

Therefore, due to the shape of the face 29, the pressure exerted by the spring on the head 3 and hence on the bottle is kept constant. An adjusting screw 31 is provided to increase or decrease the tension of the 70 spring as desired. This arrangement of the spring is more fully described and is claimed in my previous application for United States Letters Patent under Serial Number 441,182 for improvements in bottle-capping machines. 75

As previously stated, the spinning head is fastened to the reciprocating plunger 32. A spline 33 may be provided engaging a groove in the plunger to prevent tendency 80 of the plunger to turn on a vertical axis. The plunger 32 is pivotally connected to a pitman 34 which is connected to a crank pin 35 in the horizontal shaft 36. A drive wheel 37, driven by power from any suitable 85 source, is loosely mounted on the shaft 36, and any suitable clutch mechanism may be employed to connect and disconnect the shaft with the drive wheel as desired. I have shown in Fig. 1, and prefer to use for 90 this purpose, a clutch mechanism invented by me and for which I have made application for United States Letters Patent under Serial No. 441,183, in which, as used herein, when the connection is made by 95 pressing down the treadle 38, the clutch is automatically disengaged after one revolution of the shaft 36 irrespective of whether or not the treadle is released.

The bottle rest 39 screws into a support 100 40 on the front of the column or standard 41. The rest 39 may therefore be adjusted vertically to adapt it to be used with bottles of various heights. The gage 42 holds the bottle in place on the rest. A plurality of holes or other means of receiving 105 the gage may be made in the column 41, as shown, thus permitting the gage to be moved accordingly as the bottle rest is adjusted.

From the foregoing description, it will appear that when the bottle is placed on the rest with the cap ready to be spun on as shown in Fig. 1, and the treadle 38 pressed down, the shaft 36 is immediately connected by the clutch to the drive wheel 37 and is rotated, thereby depressing the pitman 34, the plunger 32 and all of the parts connected thereto. The buffer-head 24 instantly contacts with the bottle-head and the screw 1 and the collar 10, the spinning rollers and other parts carried by the screw are stopped from further downward movement. Consequently the parts carried by the supporting head 2 are telescoped down into those held stationary by the bottle, and the nut 4, the sleeve 11, the collar 10 and the spinning rollers are rotated as previously described. The bearing blocks 20 of the roller carrying levers are normally slightly off 110 120 125 130

set from the helical grooves 7, and, because of lost motion between the vertical screw 1 and its nut 4, as hereinafter described, initially mount the inclined faces of the 5 grooves so that the spinning rollers are pressed in until they contact with the bottle-head and then by their rotation spin on the cap. If desired, the edges of the rollers may be scalloped as shown in Fig. 5. 10 Through the spring 27 and the rock lever 28, the pressure on the top of the bottle is kept uniform during the entire descent of the plunger and the parts carried by it, as previously described. 15 About the collar 12 is a volute spring 43, one end of which is fastened to a stud 44 on the collar 10 and the other end is fastened to the collar 12. As the collar 10 is rotated when the plunger descends, the spring 43 is 20 wound up and tends to retract the spinning mechanism. As shown in Fig. 3 the threads of the nut and screw fit loosely together and, as soon as the nut reaches its lowest limit, the rollers are reversed as far as the play 25 of the threads allow. Since the sleeve 6 meanwhile is held stationary, this has the effect of drawing the face of the bearing blocks 20 off the inclined portion of the grooves 7 and thereby allowing the springs 30 22 to push the rollers slightly back out of contact with the bottle-head and cap, the object of this being to prevent the rollers from binding on the cap and carrying the bottle along, as the nut ascends the screw 35 and the rollers are turned in the opposite direction.

While the pitch of the threads may be varied as desired, I have found that a pitch such that the parts are revolved once for 40 every three and a quarter inches is the most satisfactory.

It is obvious that various modifications may be made in the construction shown and above particularly described with the principle and scope of my invention.

I claim:

1. A bottle-capping machine comprising spinning rollers, a co-operative screw and nut adapted to rotate the spinning rollers as the 50 screw and nut are moved rectilinearly relatively to each other, and means for thus relatively moving the screw and nut.

2. A bottle-capping machine comprising spinning rollers, a stationary screw, a co-operative nut movable rectilinearly on the screw and adapted to rotate the spinning rollers during such movement and means for rectilinearly moving the nut on the screw.

3. A bottle-capping machine comprising spinning rollers, a co-operative screw and nut movable rectilinearly relatively to each other and adapted to rotate the spinning rollers as they are so moved and to reverse the rotation as the screw and nut are reversed in co-operation, means for pressing the spinning

rollers in yielding contact with the bottle-head as the nut and screw are relatively moved, and means for releasing the rollers from contact with the bottle-head at the end of such movement and before the rollers are 70 reversed.

4. A bottle-capping machine comprising spinning rollers, a stationary screw, a co-operative nut movable rectilinearly on the screw and adapted to rotate the spinning rollers during such movement, means for pressing the spinning rollers in yielding contact with the bottle-head as the nut is moved on the screw, and means for releasing the rollers from contact with the bottle-head at 80 the end of such movement.

5. In a bottle-capping machine, in combination, spinning rollers, means for pressing the spinning rollers in contact with the bottle-head and resilient means for releasing the spinning rollers from the bottle-head at 85 the completion of the capping operation.

6. A bottle-capping machine comprising spinning rollers, a screw, a co-operative screw and nut adapted to be moved rectilinearly relatively to each other and to rotate the spinning rollers and press them in contact with the bottle-head as the nut and screw are relatively moved, means for relatively moving the nut and the screw as desired, a volute spring for releasing the spinning rollers from the bottle-head before the rollers are reversed, and means for exerting uniformly yielding pressure on the bottle to hold the bottle in place during the capping 100 operation.

7. In a bottle-capping machine, a spinning head comprising spinning rollers and a co-operative screw and nut adapted to be moved relatively to each other and to rotate the 105 spinning rollers as the screw and nut are relatively moved, and means for bringing the spinning head into contact with the bottle-head thereby relatively moving the screw and nut.

8. A bottle-capping machine comprising spinning rollers, a co-operative screw and nut adapted to be moved rectilinearly relatively to each other and to rotate the spinning rollers as the screw and nut are so relatively moved, means for pressing the spinning rollers in yielding contact with the bottle-head as the nut and screw are relatively moved, and means for releasing the rollers from contact with the bottle-head at 115 the end of such relative movement of the screw and nut.

9. In a bottle-capping machine, in combination, spinning rollers, means for actuating the spinning rollers, means for pressing the spinning rollers in contact with the bottle-head, and resilient means for releasing the spinning rollers from the bottle-head at the completion of the capping operation.

10. In a bottle capping machine, in com- 130

bination, cap-applying means adapted to be pressed into engagement with the bottle neck and to apply the cap, means for operating the cap-applying means, and resilient means for releasing the cap-applying means from the bottle head at the completion of the capping operation.

In testimony whereof I affix my signature in presence of two witnesses.

HERBERT E. MARSHALL.
